MULTIPLE ROLL-SET BOARD DROP
HAMMER

Michael H. Flynn, Hartford, Conn., assignor to
The Billings & Spencer Company, Hartford,
Conn., a corporation of Connecticut

Application May 3, 1926. Serial No. 106,423

8 Claims. (Cl. 78—29)

The object of the invention is an improvement in the mechanism for causing the lifting rolls of the several sets to bear simultaneously and equally upon the hammer board. These rolls and their supports and the members which move the latter are ponderous structures but are required to move quickly into and out of board-gripping position and some considerable difficulty has been encountered, under these conditions, in causing them to exert substantially equal pressure on the hammer board as well as in causing them to release the board simultaneously. Failure of the rolls to act in close unison when engaging, as well as when disengaging, the board interferes with sustained reciprocation of the hammer, besides injuring and shortening the life of the board. The present invention overcomes the difficulties referred to, by the use of mechanism simple in form and the least subject to derangement, under the severe conditions of drop hammer use. The invention consists in the organization of the means and in the principle thereof as hereinafter explained.

In the drawings, Fig. 1 is a front elevation of a four roll board drop hammer having the invention applied.

Fig. 2 is a larger scale side elevation of the roll head in Fig. 1.

Fig. 3 is a large scale front elevation thereof.

Fig. 4 is a top plan of the roll head with parts removed.

Figs. 5, 6 and 7 are respectively diagrammatic representations of modified forms of pressure-equalizing linkage within this invention.

The hammer comprises a base 1, two uprights 2, between which the hammer 3 is guided, and a roll head structure 4, joining the top of the uprights, and in which the lifting rolls and their control means and also the board clamp are mounted.

The rolls of the upper pair or set are marked 5 and 5^a, respectively, and those of the lower set, 6 and 6^a. All of the rolls are fixed on roll shafts 7 and the latter are journalled in bushings 8, which, in turn, are journalled eccentrically to the shafts, in the frame structure 4, which latter may be of any suitable design. Each eccentric bushing or sleeve 8 is provided with a radial actuating arm 9 and the two arms, for each roll, are rigidly united by a cross pin. Such cross pins are marked 10 and 11 for the eccentric roll supports of the two rear rolls respectively and 12 and 13 for the corresponding actuating arms of the front rolls. In each case the cross pins are firmly clamped in the ends of their arms 9 which latter are split

and provided with bolts for that purpose and as indicated. The rolls 5 and 5^a of the upper roll set are geared together by gears 14 and driven by pulley 15 fixed to the extended end of the rear roll shaft, and similarly, the lower rolls 6 and 6^a are geared together by gears 16 and driven by a pulley 17 fixed on the rear roll shaft at the opposite side of the machine. The two pulleys will be understood to be belted to a common overhead drive shaft and driven in the same direction. 65

The eccentricities of the upper roll supports or bushings 8 are equal but opposite to the eccentricities of the lower roll supports, so that movement of the upper and lower arms 9 toward or from each other, that is to say in mutually opposite directions produces bodily movement of the corresponding rolls toward or from the hammer board, that is to say, in the same direction. In the present case a separating movement of the two front arms 9 produces movement of the two front rolls 5 and 6 toward the hammer board, but this can be reversed if desired by reversing the direction of the eccentricity of each bushing with the same ultimate effect. Movement in the same direction, of the rear roll arms produces similar 80 movement of the rear rolls, but these rolls are intended to be fixed and the movement of the arms is for adjustment only. For this purpose the vertical rod 18 is connected to the cross-pin 10 of the eccentric bushings of the upper rear rolls and to 85 pin 11 of the lower rear roll and rod 19 is similarly connected to the cross-pin 11 of the lower roll. The lower end of this rod 19 is provided with nuts placed on opposite sides of fixed frame lug, such as 20 (Fig. 2) so that the rod can be longitudinally 90 adjusted thus to hold the rear rolls in proper fixed relation to the hammer board.

The upper and lower actuating arms 9 of the front rolls are connected by toggle links 21 and 22, the middle or toggle joint of which is formed by 95 a toggle pin 23. These links are jointed to the cross-pins 12 and 13 respectively and their weight is entirely carried by the arms 9. The toggle pin 23, which connects the links is also supported by the arms 9 and this pin is connected by a floating 100 link 24 to the upright arm of a bell crank 25 fulcrumed on an appropriate bracket or lug on the main frame. The lower horizontal arm of this bell-crank is jointed to the upper offset end of the friction bar 26, or to such other hammer-operated mechanism as may be employed for producing the board-gripping movement of the lifting rolls. Where the ordinary friction bar serves this purpose, the weight of the latter tends to rock the bell crank and thereby pull the link 110

24 and the toggle pivot 23 outwardly, thus expanding the toggle so as to spread the arms apart and this presses both rolls 5 and 6 into gripping relation to the hammer board 3^a. Inasmuch as 5 the roll-actuating arms 9 and the toggle links are respectively of equal radii and make equal angles with each other and with the link 24, it will be apparent that the pressure is transmitted with substantial equality to each roll set. As shown 10 in Fig. 3 and for the sake of symmetry, the toggle links 21 and 22 are each formed in pairs disposed on opposite sides of the link 24, this arrangement being desirable but not essential.

The lower end of the friction bar 26 is guided 15 as usual in a box 26^a containing a catch to hold it elevated. This structure is not shown in the drawings because it is very common in the art. It will be understood that the catch is operated by the cam surface 27 on the hammer proper when the 20 latter falls, and thus releases the friction bar, allowing it to drop. The drop of the friction bar moves the rolls against the board by the means above just described and the rotation of the rolls lifts the hammer. Toward the end of the hammer's 25 upstroke, its stud 28 engages the friction bar lever 29 again lifting the latter to its catch-supported position, simultaneously releasing the roll pressure so that the hammer again falls and so on thus producing sustained reciprocation. In 30 order to prevent such operation, the board clamp treadle 30 is released, thereby bringing the board clamp mechanism, represented generally by 31 (Fig. 2) into action to hold the board in an elevated position, all as customary in this art.

35 Referring to Fig. 5, the actuating arm 5 of the upper and lower front rolls, marked 32 and 33 in this figure, are connected by toggle links 32 and 35 as before, but the toggle pin 36 in this case is moved toward and from its dead center line by 40 means of force applied to it through the lower link 35 instead of through a floating link such as 24 in Fig. 2, that is to say, by means of an arm 35 rigidly formed on said lower link and extending at an angle thereto. The friction bar is connected 45 to this extended arm so that its weight is transmitted substantially equally to both of the roll actuating arms and hence to their rolls 5 and 6.

In Fig. 6 the same principle will be seen to be 50 employed, but in this case the upper toggle link is provided with the extension 38 to which the friction bar is connected so that the weight of the bar tends to collapse the toggle instead of expanding it.

In Fig. 7 the weight of the friction bar is transmitted 55 to the links so as to expand the toggle. In this case, the bar is jointed to one arm of a bell crank 39, and the other engages a slot in the end of the arm 40, which, like the arm 37 of Fig. 5, is an angular extension of one of the toggle links. The direction of the force exerted in this 60 manner on the arm 40 is substantially parallel to the radius of the lower arm 9 and hence such force is without tendency to rock that arm except as it rocks the toggle links and thereby moves both arms in unison and with equal pressure.

Figs. 5, 6 and 7 represent practical forms of the 70 present invention, but no attempt has been made to illustrate all of the possible embodiments of the toggle principles employed and such as may obviously be incorporated in various forms to produce substantial equality of roll gripping pressure as between the different sets of rolls.

I claim:

75 1. In a multiple roll-set board drop hammer, the combination of a hammer board, two pairs

of board-lifting rolls therefor, a movable support for one roll of each pair, an actuating arm for each roll support, means whereby the movement of said arms in opposite directions moves said rolls in the same direction, and hammer controlled mechanism for simultaneously oppositely moving said arms.

2. In a multiple roll-set board drop hammer, the combination of a hammer board, two pairs of board-lifting rolls therefor, a movable support for one roll of each pair, an actuating arm for each roll support, means whereby the movement of said arms in opposite directions moves said rolls in the same direction, a friction bar and means connecting the same to said arms adapted for transmitting the weight of said bar substantially equally to said arms and in opposite directions.

3. In a multiple roll-set board drop hammer, the combination of a hammer board, two pairs of board-lifting rolls therefor, a movable support for one roll of each pair, an actuating arm for each roll support, means whereby movement of said arms in opposite directions moves said rolls in the same direction, connecting means 100 between said arms supported entirely thereon and adapted for coincidentally moving said arms in opposite directions, and hammer-controlled mechanism connected to actuate said connecting means.

4. In a drop hammer, the combination of a reciprocating hammer board, two vertically disposed pairs of power-driven lifting rolls, arms appurtenant to one upper and one lower roll respectively and adapted for movement in opposite directions for simultaneously moving both rolls toward said board, connecting means between said arms supported by them, a floating link for imparting movement to said connecting means and hammer-controlled mechanism for 115 moving said link.

5. In a board drop hammer, the combination of upper and lower lifting rolls, an eccentric sleeve supporting one upper and one lower roll, the eccentricities being of opposite directions and hammer controlled means for simultaneously and oppositely rocking said supports.

6. In a board drop hammer, the combination of upper and lower lifting rolls, eccentric sleeves 125 supporting the roll shafts of each such roll, the eccentricities of the upper and lower sleeves being opposite in direction, substantially horizontal arms on said sleeves and means controlled by the reciprocation of the hammer adapted for simultaneously spreading and collapsing said arms.

7. In a drop hammer, the combination of a hammer board, upper and lower pairs of power driven lifting rolls active on opposite sides of said board, actuating arms for moving such rolls toward and from the board, a pair of links connected together and connecting said arms and means active in synchronism with the hammer for operating said links toggle fashion, in one direction putting both links simultaneously under tension to draw said actuating arms together and means to thereby move the rollers in the same direction with respect to board gripping action, and in the opposite direction putting them simultaneously under compression to spread said 145 arms apart and move the rolls in a direction opposite to that produced by moving the arms together.

8. In a board drop hammer, the combination of a hammer board, upper and lower lifting rolls 150

each driven independently of said board, an actuating member for each roll adapted to move it toward or from the board, links connecting said members to spread them apart or move them toward each other by toggle action depending upon the direction of movement, a friction bar reciprocated by the hammer, means connecting

said bar to said links and means operating to put both of said links coincidently under compression and to produce one and the same direction of roll movement with respect to board gripping action and under tension for the other and opposite direction of roll movement. 80
